SIGN

James G. Juhasz, Chicago, Ill., assignor to Joseph Weidenhoff Incorporated, a corporation of Illinois

Application July 13, 1931. Serial No. 550,531

11 Claims. (Cl. 40—130)

The invention relates to signs and particularly to illuminated signs of the type shown and described in my co-pending application, Serial No. 524,733, filed March 23, 1931.

5 Signs of this type comprise panels of light pervious material upon which advertising data or the like, is painted or written. Light is projected into the panel through an edge thereof and the result is that the light is projected from or 10 through the painted surface with an intensity that causes the surface to stand out in bold relief. In some instances, it is desirable to paint a considerable amount of data upon these signs to color considerable areas thereof. It has been 15 found that when such is the case, the data or colored surfaces adjacent the source of light will be intensely illuminated, but data or colored areas at greater distances from the source of illumination will remain comparatively dull.

20 It is the primary object of the present invention to provide a sign of the character described which is adapted to have a relatively large amount of advertising data thereon intensely illuminated when the sign is in operation.

25 Other objects and advantages will become apparent as the following description progresses, reference being had to the accompanying drawing wherein:

Figure 1 is a front elevation of a sign which 30 embodies the invention.

Fig. 2 is an enlarged section taken on line 2—2 of Fig. 1.

Fig. 3 is a section taken on line 3—3 of Fig. 2, and

35 Fig. 4 is an enlarged section taken on line 4—4 of Fig. 3.

Referring to the drawing wherein a preferred embodiment of the invention is illustrated, the reference character 10 designates a housing mem- 40 ber which carries a sign 11.

The housing member 10 comprises end plates 12 and 13 and sheet metal housing members 14, the sheet metal housing members 14 being secured to the end plates 12 and 13. The upper 45 edges of the housing members 14 are spaced from each other and the opening therebetween is closed by a cover plate 15 secured to the end plates.

Secured to the end plates 12 and 13 to extend 50 downwardly therefrom are channel members 16 which are joined at their lower ends by a horizontally extending channel member 17. The channel members 16 and 17 carry glass panes 20 and 21 and backing members or sheets of paper 22 and 23. The sheets of paper 22 and 23 are 55 disposed between the glass panes 20 and 21. The

back surface of the glass pane 20 is spaced from the opposed surface of the paper 22.

The upper edges of the glass panes 20 and 21 project up into the housing 10 so that an incandescent lamp 25 disposed in the housing may project light down through the glass panes. The lower edges of the housing members 14 are provided with rubber gaskets 27 which fit snugly against the upper surfaces of the glass panes and prevent a leakage of light at these points. 60 As shown, reflectors 29 disposed within the housing 10 are adapted to reflect the light of the lamp 25 in such a manner that a relatively large amount of it will be projected down through the glass panes. 65

As best shown in Figures 1, 3 and 4, advertising data designated generally by the reference character 30 are painted on and associated with the glass panel 20. Thus the outlines of the letters forming the word "flowers" are painted upon the 70 back surface of the glass pane 20 in any suitable color or colors. The outlines for these letters are relatively narrow lines and when light is projected down through the glass pane 20 by the lamp 25, the light will be projected from the 75 outlines of the letters in such manner that the outlines will stand out in bold relief against the remainder of the glass pane. However, as the outlines are relatively narrow, comparatively little of the light travelling through the glass pane 20 will be projected from the glass pane by the outlines forming the letters and additional data may be painted upon the lower part of the glass pane 20 and this additional data will be 80 illuminated to substantially the same extent as 85 the outlines of the letters forming the word "flowers".

The sheets of paper 22 and 23 are black or some dark color which does not reflect an appreciable amount of light. The portions of the sheet of 90 paper 22 which are disposed within the areas defined by the outlines for the letters forming the word "flowers", are painted white or some light color so that these portions will stand out in bold 95 relief against the remaining portions of the back- 100 ing sheet of paper 22. The result is that when the sign is illuminated, the outlines for the letters forming the word "flowers", co-operate with the painted surfaces on the backing paper 22 to form 105 letters which are visible for relatively long distances. Of course, none of the light travelling through the glass pane 20 strikes the painted portions of the backing paper 22 and therefore a com- 110 paratively small amount of light is utilized to form

the word "flowers" in bold relief against the glass pane 20.

Figure 4 illustrates in detail the manner in which the coatings are applied to the glass pane 20 and the backing paper 22. The section is taken through the letter "S" and the outlines formed by coatings for this letter are indicated at 32 on the glass pane 20. The coatings on the backing paper 22 are shown at 33. These coatings form the body portions of the letters. It would be noted that the coating 33 is alined with the outlines 32 formed on the glass pane 20. The coating 33 is preferably of a different color than the outline 32.

The glass pane 21 is provided so that one may write with crayon or paints upon the exposed surface thereof. Then when the lamp 25 projects light down through the glass pane 21, the light will be projected through the paint or crayon which will be illuminated and will stand out in bold relief against the glass pane 21.

The sign associated with the glass pane 20 is preferably of a permanent character, while the sign associated with the glass pane 21 may be altered at will.

The sign shown in the drawing is preferably adapted to be suspended in a show window or the like. For this purpose, the housing 10 is provided with hooks 35, to which cords may be attached.

The backing member 22 has additional lettering 44 which is visible through the glass 20 and does not utilize any of the light projected into this glass.

It will be readily understood, that signs embodying the invention may be constructed with a considerable amount of lettering thereon or with relatively large intricate designs. Relatively small areas of the letters or of the designs are formed by painting or writing directly upon the glass panel and therefore a relatively small amount of light is dissipated through the coatings formed by painting or writing on the glass panel. The body portions of the designs or letters are formed by coloring the backing member in any manner desired. Thus, in other embodiments of the invention, outlines of a design or outlines of letters are painted or written, in the manner described, upon the glass panes and the backing members are colored with various colors which do not include necessarily dark colors. Some of the colored portions co-operate with the outlines on the glass pane to complete the designs or letters and to make them stand out against the glass panes even though the panes are not illuminated. Of course, when the panes are illuminated in the manner described above, the outlines of the letters or designs project a relatively intense light and the body portions of the designs are formed by the colored portions which have been placed upon the backing members.

The term "design" is employed generally in the appended claims to include ornamental designs, lettering, etc., an ornamental design is shown at 40 in the drawing. It consists of outlines 41 on the pane 20 and body portions 42 on the backing member 22.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible, in view of the prior art.

What I claim as new, and desire to secure by Letters Patent, is:

1. A device of the kind described comprising a plate of light pervious material having portions of a design marked thereon, a dark colored 80 backing member for said plate, light colored coatings on said backing surface completing the design on said plate, and means for projecting light into said plate through an edge thereof.

2. A device of the kind described comprising 85 a plate of light pervious material, coatings on said plate forming the outlines of data to be displayed, a dark colored backing for said plate, said backing member having light colored portions forming the body portions of said data, 90 and means for projecting light into said plate through an edge thereof.

3. A device of the kind described comprising a plate of light pervious material, a coating adhering to a surface of said plate, a dark colored 95 backing member for said plate, a light colored coating on a portion of said backing member, said light colored coating being visible through said plate and said coatings co-operating to form display data, and means for projecting light 100 into said plate through an edge thereof.

4. A device of the kind described comprising a plate of light pervious material, data painted on a surface of said plate, a backing member for said plate, said backing member having a light 105 colored portion co-operating with said data painted on said plate, and means for projecting light into said plate through an edge thereof.

5. A device of the kind described comprising a plate of light pervious material having painted 110 portions, a dark backing member for said plate having light colored portions co-operating with said painted portions, and means for projecting light into said plate through an edge thereof.

6. A device of the kind described comprising a 115 plate of light pervious material having portions of a design marked thereon; a backing member for said plate and spaced therefrom, said backing member having differently colored portions visible through said plate, some of the last mentioned portions being portions of said design, and means for projecting light into said plate 120 through an edge thereof.

7. A device of the kind described comprising a plate of light pervious material having outlines 125 of a design marked thereon, a backing member for said plate and spaced therefrom, said backing member having differently colored portions visible through said plate, some of said portions being alined with said outlines to form the body 130 portions of said design, and means for projecting light into said plate through an edge thereof.

8. A device of the kind described comprising a plate of light pervious material having outlines of letters marked thereon, a backing member 135 for said plate and spaced therefrom, said backing member having differently colored portions visible through said plate, some of said portions being alined with said outlines to form the body portions of said letters, and means for projecting light into said plate through an edge thereof.

9. A device of the kind described comprising a plate of light pervious material having portions of a design marked thereon, a dark colored 145 backing member for said plate, light colored coatings on said backing surface completing the design on said plate, and means for projecting light into said plate so that most of it travels 150

edgewise thereof and back and forth between the front and back surfaces thereof.

10. A device of the kind described comprising a plate of light pervious material, coatings on said plate forming the outlines of an inscription, a dark colored backing for said plate, said backing member having light colored portions forming parts of said inscription, and means for projecting light into said plate so that most of it travels edgewise of said plate and back and forth between the front and back surfaces thereof. 80

10 travels edgewise thereof and back and forth between the front and back surfaces thereof.

11. A device of the kind described comprising
